UNITED STATES PATENT OFFICE.

MICHAEL H. DEGNAN, OF NASHUA, NEW HAMPSHIRE.

SELECTIVE SIGNAL FOR TELEPHONE SYSTEMS.

No. 835,704.

Specification of Letters Patent.

Patented Nov. 13, 1906.

Application filed February 20, 1906. Serial No. 302,017.

To all whom it may concern:

Be it known that I, MICHAEL H. DEGNAN, a citizen of the United States, residing at Nashua, in the county of Hillsboro and State 5 of New Hampshire, have invented new and useful Improvements in Selective Signals for Telephone Systems, of which the following is a specification.

This invention is a selective ringing device 10 or call for party-line telephones or the like, and has for its object to provide an improved device of the kind.

It embodies an electromagnet in the line-circuit operating an armature and a pawl and 15 ratchet to turn a cam-shaft, together with a circuit-closer consisting of a rocking box having a tortuous passage therein containing a ball which when it runs to the end of the passage closes the circuit, the movement of the 20 box being controlled by a follower which rests upon the cam.

The construction will be more evident from the following description and the accompanying drawings.

25 In the drawings, Figure 1 is a perspective view, partly diagrammatic, of the invention. Fig. 2 is a top view partly in section. Fig. 3 is a view showing the arrangement of the cams at the different stations. Fig. 4 is a 30 side elevation showing the outer casing and dial.

Referring specifically to the drawings, 10 indicates a casing or box in which the mechanism is contained. This has a dial 11, provided 35 with numbers corresponding to the number of the station, the numbers shown being from "1" to "7," with a blank station, or starting-point indicated by "0" when the line is not in use.

40 The line-wires are indicated at 12, connected to an electromagnet 13. The armature 14 of this magnet is pivoted on a standard 15 and carries at its outer end a pawl 16, which is engageable with a ratchet-wheel 17, 45 mounted on a shaft 18, which carries the pointer 19^a for the dial. The teeth of the wheel correspond in number and position to the number of stations and the numbers on the dial. The shaft 18 has thereon a cam 50 19, provided with a low point, as at 20. At 21 is indicated a box mounted to rock upon a shaft 22, supported by a standard 23. The box has a tortuous or zigzag passage or run 24, containing a metal ball 25. The shaft 22 55 has a laterally-projecting arm 26, with a roller 27, resting as a follower upon the edge of the

cam 19. At 28 are indicated telephone signal-bells connected on one side to the main line and on the other side to one of a pair of conducting-posts 29, the other of which is 60 connected to the other side of the main line. These posts stand side by side under the box 21. At the end of the runway the box has an opening 30, and the parts are so arranged that when the box is turned down the posts 65 29 will extend into the opening 30 and be connected across by the ball 25, thereby closing the bell-circuit. A spring 31 is connected to the box and holds the follower to the cam.

70 The cams at the different stations will be so set on their respective shafts that the notches or low points of the cams will correspond in position to the numbers of the respective stations on the dial and the respective teeth on the ratchet, as illustrated in Fig. 3.

75 The tilt or rock of the box is controlled by the cam. The parts are so arranged that when the follower is on the high points of the 80 cam the box is tilted so that the ball will be at the rear or closed end of the runway. When the follower is at the low point of the cam, the front edge of the box is tilted so that the ball will run down to the posts of 85 the bell-circuit and close the same. Some little time is required for the ball to run down the zigzag way, and this time is utilized to allow the calling-station to pass stations not wanted by short or quick movement of the operating mechanism, the impulses over the line being sent by any of the means usually used for that purpose. Thus one desiring to call station No. 5 will send five impulses over the line, the first four being short and the fifth long. At each impulse the box will of course tilt at one of the stations; but the first four impulses being short sufficient time will not elapse for the ball to roll down the runway before the cam 90 is again turned, which will turn the box back; but the fifth impulse being long will give time for the ball to run down to the posts and so close the bell-circuit at station No. 5, as desired, and the bell will ring there as long 95 as the current is held on. The pointers of the dials of all the stations will be correspondingly moved and will indicate to all the stations that the line is busy and may not be interrupted. When the call is finished, the 100 parts are returned to original position by giving enough short impulses (three in the in-

stance specified) to bring the parts to the "0" position. This leaves the line ready for next use.

I claim—

1. The combination with the shaft having a cam and a station-index thereon, of the tilting box having a follower which rests upon the cam, and a circuit-closing roller in the box.
2. The combination of a tilting box having a tortuous runway therein, and a circuit-closing roller in said runway, of a shaft having a selective cam thereon, connections between the cam and the box to tilt the same according to the position of the shaft, and means connected to the main line to turn the shaft.
3. In a selective signaling system, the combination at a station of a shaft having a station-index and a selective cam thereon, a tilting box having therein a zigzag runway, a roller in the runway, a pair of contact-pieces

in the bell-circuit and under the end of the runway, and a follower resting on the cam and connected to the box, to control the tilt thereof.

4. The combination with the bell-circuit having a pair of contacts therein, of a tilting box having a runway with an opening at the end above the contacts and into which said contacts project when the box is tilted down, a ball in the runway, constructed to connect the contacts and close the circuit, and means connected to and controlled by the main line to tilt the box.

In testimony whereof I have signed my name to this specification in the presence of two subscribing witnesses.

MICHAEL H. DEGNAN.
